UNITED STATES PATENT OFFICE.

GEORGE H. OBER, OF CHAGRIN FALLS, OHIO.

DESIGN FOR A SAD-IRON HANDLE.

SPECIFICATION forming part of Design No. 23,525, dated July 31, 1894.

Application filed January 13, 1894. Serial No. 496,809. Term of patent 14 years.

To all whom it may concern:

- Be it known that I, GEORGE H. OBER, a citizen of the United States, residing at Chagrin Falls, in the county of Cuyahoga and State of Ohio, have invented and produced a new and original Design for Sad-Iron Handles, of which the following is a specification, reference being had to the accompanying drawings, showing a part thereof.
- 10 Figure 1 is a side view of a sad-iron handle showing my design; Fig. 2, an end view of the same, and Fig. 3, a sectional view on line x, x , Fig. 1, these three views being deemed necessary to fully illustrate my design.
- 15 The leading features of my design consist of a curved grip which takes the form of an arc of a circle and the standard composed of a straight base with curved end pieces extending upward therefrom to meet said grip.
- 20 The grip 1 is round in cross section and in the form of an arc of a circle embracing about eighty-five degrees. Each of the ends 1^a is cut at an angle of thirty-five degrees more or less.
- 25 The standard 2 consists of the straight base 3 having the oval top 3^a and the end pieces 4, 4. The base 3 terminates at each end in the projection 3^b . Each end piece 4, at the top, conforms to the angle of the end 1^a , of the grip 1, to which it is connected and by a graceful, outward curve for the greater part of its length joins the base 3. The edge 4^a of each piece 4 extends the entire length of said piece

both sides, taking the form of a compound curve, as shown in Figs. 2 and 3, and is a continuation of the perpendicular sides 3^c of the base 3. The internal, oval surface 4^b , of each piece 4, is a continuation of the oval top 3^a , of the base 3, and terminates at the end of the grip 1. The exterior oval surface 4^c , of each piece 4, conforms to the outer line of the edge 4^a except at the base where said oval surface and edge line come together, at the point of the projection 3^b . Said oval surface 4^c changes near the top and at the bottom 45 from an outward to inward curves, as does the outside line of the edge 4^a , while the inside line of said edge changes to the inward curve only near the top.

What I claim is—

The design for a sad iron handle consisting of the grip 1, round in cross section and in the form of an arc of a circle of about eighty-five degrees, the straight base 3 having the oval top 3^a , the projection 3^b , and the perpendicular sides 3^c , and the end pieces 4, 4 having the edges 4^a , the internal oval surfaces 4^b , 4^b , and the external oval surfaces 4^c , 4^c , substantially as shown and described.

In testimony whereof I affix my signature in presence of two witnesses.

GEORGE H. OBER.
